DISPLAY STAND

Howard J. Marschak, Chicago, Ill.

Application July 29, 1957, Serial No. 47,138

Term of patent 14 years

(Cl. D80—9)

The figure is a left front perspective view of a display stand, embodying my new design, the right side being substantially like the side shown.

The rear of the display stand is plain and tapers upwardly on both sides as is shown by the drawing.

I claim:

The ornamental design for a display stand, as shown and described.
